SPUD ASSEMBLY FOR A TANK AND METHOD OF ATTACHING SAME

Harold L. Emmons, Kankakee, and Joseph Maravolo, St. Anne, Ill., assignors to A. O. Smith Corporation, Milwaukee, Wis., a corporation of New York

Application September 13, 1956, Serial No. 609,635

2 Claims. (Cl. 219—93)

This invention relates to a spud assembly and to a method of attaching the same to a wall of a tank or vessel.

In a tank such as a hot water heater, spuds are secured within openings in the tank wall and provide a means for connecting threaded nipples or pipes to the tank. As a hot water heater tank is generally made of ferrous material and is subject to corrosion from the contained liquid, a cathodic protection system is employed to prevent the corrosion of the tank wall, and in order to reduce the amount of exposed metal of the tank wall to be protected by the cathodic system, the inner surface of the tank is generally lined with a coating of glass or vitreous enamel.

In coating a tank with glass, one of the biggest difficulties has arisen in coating the spud which projects into the interior of the tank. More particularly, the inner corner or fillet where the spud joins the tank wall and the inner edge of the spud are difficult to satisfactorily coat with glass. In many cases these areas are not adequately coated with the result that the amount of bare or exposed metal in the tank is increased and this, of course, reduces the effective life of the anode.

The present invention is directed to a spud assembly which eliminates all projections on the inside of the tank and locates the spud solely on the outside of the tank wall. More specifically, the spud is provided with an opening of substantially the same diameter as the opening in the tank wall and the spud is disposed so that the openings are axially aligned. The spud is resistance welded to the outer surface of the tank wall and a thread is formed in the annular surfaces of the tank wall and the spud which border the aligned openings so that the thread extends continuously from the inner surface of the tank wall to the outer surface of the spud.

With this construction there is no projection on the inner surface of the tank with the result that the tank wall can be coated with glass and the glass coating will extend directly to the threaded opening.

In addition, the present spud construction is adapted for use on both heads and cylindrical shells of the tanks and therefore simplifies the manufacturing procedure over that of conventional practices in which different types of spuds are used for the heads and the shell.

The method of attaching the spud of the invention reduces the overall cost of the water heater by decreasing welding problems and improving the assembly operations.

Furthermore, an improvement in the threads is obtained with the present invention because a harder steel can be employed for the spud and closer tolerances are possible on the inside diameter of the spud for tapping.

Other objects and advantages of the invention will appear in the course of the following description.

The accompanying drawing illustrates the best mode presently contemplated by the inventor for carrying out the invention.

In the drawing:

Figure 1 is a perspective view of the spud assembly as secured to a water heater head;

2

Fig. 2 is a vertical section showing the attachment of the spud to the head;

Fig. 3 is a transverse section of the spud before welding to the head;

Fig. 4 is a vertical section of the die assembly employed to weld the spud to the head; and

Fig. 5 is a view similar to Fig. 4 showing the position of the die elements during the welding operation.

The drawing illustrates a water heater head 1 to which the spud assembly of the invention is secured. The head 1 is formed of sheet metal and is adapted to enclose the upper open end of a cylindrical water heater shell or tank, not shown. The head 1 is formed with a generally flat portion 2 which is provided with an opening 3. An annular spud 4, having an opening 5 corresponding in diameter to opening 3, is disposed in axial alignment with opening 3 and is secured by weld 6 to the outer surface of head 1.

The inner annular surface of the spud 4 bordering the opening 5 and the inner annular surface of the head 1 bordering opening 3 are tapped to provide a thread 7 which extends continuously from the inner surface of the head 1 to the outer surface of the spud 4.

The inner surface of head 1 may be coated with a glass or vitreous enamel material 8 which extends to a position immediately adjacent the thread 7.

The spud itself, before being welded to the tank head 1, is formed with three annular concentric ridges 9, 10 and 11. This is best shown in Fig. 3. The central ridge 10 has the greatest height of the ridges and is adapted to initially contact the tank head 1 and this annular biting contact provides a small contact area for accomplishing resistance welding of the spud to the tank wall.

The inner ridge 9 and the outer ridge 11 serve to confine the molten weld metal during welding and tend to prevent spattering of the same. The ridge 9 is particularly important so as to prevent the weld metal from flowing into the aligned openings 3 and 5. If a considerable quantity of weld metal penetrates into the openings, a reaming operation may be necessary in order to clear the openings before the thread 7 is tapped therein. Ridge 9 under normal conditions traps the metal and eliminates the reaming operation.

As shown in Figs. 4 and 5, the die assembly for welding the spud 4 to the head 1 includes a fixed lower die 12 which is secured to a suitable base, not shown. The lower die 12 is provided with an axial recess 13 and a series of access openings 14 extend through the wall of the die 12 and communicate with the recess 13.

The upper end of the recess 13 receives a die plunger 15 and the plunger 15 is adapted to be inserted within the opening 3 in head 1 to align the head for welding.

The die plunger 15 is retained within recess 13 by a dowel pin 17 which extends through an opening 16 in the lower portion of plunger 15.

The die plunger 15 is biased upwardly by means of a spring 18 so that the upper end of the plunger projects upwardly beyond the upper surface of the lower die 12. Spring 18 extends between the bottom of recess 13 and the lower surface of plunger 15.

A movable upper die 19 is disposed in axial alignment with lower die 12 and is provided with an axial recess 20 which receives a plunger pin 21. The outer end of pin 21 extends a substantial distance beyond the lower surface of die 19. Pin 21 is maintained out of electrical contact with the upper die 19 by an insulating material 22 which is disposed within the recess 20.

Electrical energy is supplied to the dies 12 and 19 by leads, not shown so that when the upper die 19 mashes spud 4 against tank head 1, a current will flow between the dies to heat the spud and the tank head.

In operation, the opening 3 in head 1 is initially pierced

by conventional procedures. The head 1 is then placed on the lower die 12 so that the die plunger 15 projects through the opening 3 in the head.

The spud 4 is then placed around the upper end of the die plunger 15 with the ridges 10 bearing against the outer surface of the head 1. The inner diameter of the spud 4 and the opening 3 have a diameter which is slightly greater than the diameter of plunger 15 so that the openings 3 and 5 are disposed in substantial axial alignment.

The upper die 19 is then moved downwardly and electrical energy is supplied to the dies. As the upper die 19 moves downwardly, plunger pin 21 held therein contacts the upper surface of die plunger 15 forcing plunger 15 downwardly against the force of spring 18. Further downward movement of the upper die brings the lower surface 23 of die 19 into contact with the spud 4 and mashes the spud into the tank head 1 which is held firmly against the upper surface 24 of lower die 12.

After a sufficient time to weld the spud to the head, the upper die is moved upwardly and the welded article is removed from the lower die.

The openings 3 and 5 are then tapped by conventional procedures to provide the thread 7 which extends from the inner surface of the tank 1 to the outer surface of spud 4.

After tapping, the inner surface of the head is coated with the glass composition 8 and fired at an elevated temperature to fuse the glass to the head.

The present invention provides a spud assembly which eliminates all projections on the inner surface of a tank and thereby substantially eliminates the problems connected with glass coating of conventional spud structures. Furthermore, as the head wall is threaded and thereby contributes to the total length of the thread, the spud itself can be reduced in thickness and this provides a material savings.

While the above description is directed to the attachment of the spud to a tank head, it is contemplated that the spud may be attached to a cylindrical shell or any other portion of the wall of a tank or vessel. Similarly, while the above procedure described the glass coating being applied to the head after the thread 7 is tapped, it is contemplated that the procedure can be reversed so that glass coating 8 is applied and fused to the tank wall before the thread 7 is tapped.

Various modes of carrying out the invention are contemplated as being within the scope of the following claims particularly pointing out and distinctly claiming the subject matter which is regarded as the invention.

We claim:

1. In a method of fabricating a hot water storage tank, the steps of forming an opening in a wall of the tank, securing an annular spud to the outer surface of said wall in concentric relation to the opening in said wall, tapping a thread through the opening in the spud and through the opening in the tank wall with the thread extending substantially continuously from the inner surface of the tank wall to the outer surface of the spud, and coating the inner surface of the wall to the edge of the opening therein with a vitreous enamel composition, said spud being located wholly on the outer surface of the wall serving to maintain the inner surface of the wall substantially free of projections and facilitate application of said vitreous enamel composition.
2. In a method of fabricating a head for a hot water storage tank, the steps of forming an opening in said head, welding an annular spud to the outer surface of said head, said spud having a central opening of substantially similar diameter to the opening in said head and said opening in said spud being disposed in alignment with the opening in said head, tapping a thread through the aligned openings with the thread extending substantially continuously from the inner surface of the head to the outer surface of the spud, and coating the inner surface of the head to the edge of said opening therein with a vitreous enamel composition, said spud being located wholly on the outer surface of the head serving to eliminate internal projections and facilitate application of said vitreous enamel composition.
